UNITED STATES PATENT OFFICE.

ROLLIE A. BROWN, OF PACIFIC GROVE, CALIFORNIA.

MONUMENT.

1,397,483.

Specification of Letters Patent. Patented Nov. 15, 1921.

Application filed March 10, 1919. Serial No. 281,791.

To all whom it may concern:

Be it known that I, ROLLIE A. BROWN, a citizen of the United States, and a resident of Pacific Grove, in the county of Monterey and State of California, have invented certain new and useful Improvements in Monuments; and I do hereby declare the following to be a full, clear, and exact description of the invention, such as will enable others skilled in the art to which it appertains to make and use the same.

This invention relates to improvements in monuments and more particularly to such as are employed as markers for graves,—one object of the invention being to provide a monument of the type specified which may be constructed and placed in position at a moderate cost; which shall be ornamental in appearance, and which shall be capable of successfully withstanding the influences which may be caused by weather and other conditions to which monuments are subjected.

With this and other objects in view, the invention consists in certain novel features of construction and combinations of parts as hereinafter set forth and pointed out in the claims.

In the accompanying drawings; Figure 1 is a perspective view of a monument showing an embodiment of my invention, and Fig. 2 is a sectional view of the same.

My improved monument comprises a base member 1 and an upright member 2 superimposed upon the base member,—each of said members comprising a body portion of wood, such as pine or red wood, as indicated at 3 and 4. The wooden members 3 and 4 will preferably be made separately and the wooden base portion 3 may be made with a socket 3^a to receive a tenon portion 2^a at the lower end of the upright portion 3.

The wooden base 3 is covered on its sides and bottom with non-corrodible sheet metal, and the top face of said base 3 is covered by a sheet 5^a of a similar metal having flanges 5^b which overlie the sheet metal sides and ends and secured by pins 6 of non-corrodible metal.

The wooden upright member 2 is covered on its front and back with sheet 7 of non-corrodible metal and the edge face portions of said wooden upright member have applied thereto, a continuous sheet 8 of non-corrodible metal, and this sheet is suitably bent to properly conform to the

several edge face portions of the member 2. The metal sheet 8 is provided at its edges with flanged portions 8^a notched at intervals, as at 8^b, so that said flanged portions may 60 overlie edge portions of the front and back sheets and the flanged portions may be perforated to receive fastening devices 8^c. The metal coverings for the respective wooden members may be separately prepared in 65 convenient knock-down condition so as to facilitate shipment and the metal sheets may be readily applied to the wooden parts. The two wooden members may be covered separately and then fitted together and the 70 completed structure will be light and easy to handle and will be waterproof and also weather-proof.

Instead of making the metal covering of aluminum, sheets or plates of brass, bronze 75 or other metal or material which will not be injuriously affected by weather or other influences to which monuments are subjected, may be employed.

The main or upright member 2 of the 80 monument is provided on its face with names, dates and inscriptions, which may be formed of gilded glass letters and figures cemented in place, as indicated at 9, and a plate 10 containing a photograph, may be 85 cemented to the upright member of the monument with the use of suitable waterproof cement. The plate 10 may be made of copper and coated with porcelain which may be baked on.

Instead of making the letters and figures of glass I may make them of metal, or they may be stamped in or embossed on the metal of the monument.

Various changes might be made in the 95 details of construction of my invention without departing from the spirit thereof or limiting its scope and hence I do not wish to restrict myself to the precise details herein set forth.

Having fully described my invention what I claim as new and desire to secure by Letters Patent, is:—

1. A monument comprising a wooden body portion providing a base member and a 105 separate upright member supported by said base member, sheets of non-corrodible metal on the front and back of the upright wooden member, a sheet of non-corrodible metal covering the top and sides of said upright wooden member and having flanges 110 pinned to the front and back metal sheets

and to the wooden upright member, and sheets of non-corrodible metal covering the base wooden member, the top sheet of the metal covering of the base member pinned 5 to the latter.

2. A monument comprising a base member and a separable upright body member fitted thereon, the said body member being covered on its front and back faces with 10 sheets of metal, the edge faces of said body member being covered with a metallic strip extending continuously from the bottom edge face, the edges of said strip being notched and perforated, whereby it is adapted 15 to be bent over and fitted about the edge faces of the body member and to be fastened thereto, in combination with a base member having metallic covering.

3. A monument capable of being shipped 20 in knock-down condition, comprising base and upright members of nail-receiving material, sheets of non-corrodible metal to cover the front and back of the upright member, a sheet of non-corrodible metal to 25 cover the top and sides of said upright member and having flanges overlying edge portions of the front and back sheets, said flanges having perforations for fastening devices, non-corrodible sheet metal to surround 30 the base member, and a non-corrodible metal sheet to cover the top of the base member around the lower portion of the upright member and having perforated flanges for

the accommodation of fastening means, said last-mentioned flanges to overlie upper edge 35 portions of the sheet metal which surrounds the base member.

4. A monument capable of being shipped in knock-down condition, comprising a wooden base member, a separate wooden upright member mounted on said base member, front and back sheets of non-corrodible metal on said upright member, a sheet of non-corrodible metal to cover the sides and top of the upright member, said last-mentioned sheet bent at intervals and provided with flanged edge portions notched at intervals and adapted to overlie edge portions of the front and back sheets, non-corrodible sheet metal to surround the sides, ends and 50 bottom of the wooden base member, and a sheet of non-corrodible metal to cover the top of the wooden base member and having flanges to overlie edge portions of the sheet metal for the base member, and non-corrodible fastening devices to pass through the various flanges and sheets which they overlie and enter the respective wooden members.

In testimony whereof I have signed this specification in the presence of two subscribing witnesses.

ROLLIE A. BROWN.
